INTERNAL-COMBUSTION ENGINE

Allen M. Rossman, Wilmette, Ill.

Application August 17, 1942, Serial No. 455,150

11 Claims. (Cl. 123—51)

This invention relates to power translating devices, and more particularly to such devices as, for instance, an engine, a compressor, or the like.

A preferred embodiment of the present invention, as illustrated in the accompanying drawings, comprises a two stroke cycle internal combustion engine, which operates on the Junkers principle, that is, two pistons operate in opposition in the same cylinder.

It is one of the objects of the present invention to provide an improved means for transmitting power between a crank shaft and a reciprocating piston whether the direction of transmission of power is from the piston to the crank shaft, as in an engine, or from the crank shaft to the piston, as in a compressor. In accordance with one of the principles of the present invention there is provided a straight line motion mechanism for guiding one end of the piston rod in substantially a straight line. This mechanism connects the piston rod to the crank shaft connecting rod. The straight line motion mechanism includes a walking beam pivoted on two floating supports, the parts being so proportioned that one point of the beam moves in substantially a straight line and another point thereof moves in a direction opposite to the direction of movement of the straight line motion point. One of those points of the beam is connected to the piston rod and the other point is connected to the crank shaft connecting rod.

It is a still further object of the present invention to provide an improved arrangement of the cylinders and crank case in power translating means of the above character. In the preferred exemplification of this feature of the present invention two cylinders are mounted with their longitudinal axes parallel to and spaced from one another, with the crank case located centrally between the longitudinal axes of the cylinders and with the axis of rotation of the crank at right angles to the plane determined by the longitudinal axes of the cylinders. The crank shaft preferably has two crank throws 180° apart, each crank throw being connected to diagonally opposite pistons of the respective cylinders. This arrangement produces a sturdy, compact, and balanced structure.

It is a further object of the present invention to produce a new and improved cylinder design for a water cooled internal combustion engine. The cylinder is provided with a jacket cast as an integral part thereof. The space between the cylinder and the jacket is divided into a central

water chamber and two end gas chambers, the water chamber being incommunicable with the gas chambers. The means for dividing this space into a plurality of chambers consists of a pair of end closures each of which comprises a pair of clamping rings having two concentric wedge-shaped gaskets between them so that upon clamping the pair of rings together the outer gasket is pressed radially outwardly into intimate contact with the interior of the jacket wall and the inner gasket is pressed into intimate contact with the outer periphery of the cylinder wall. This provides a water-tight, gas-tight seal while at the same time permitting relative movement of the cylinder wall with respect to the jacket wall, which movement takes place when the cylinder expands by heating.

It is a still further object of the present invention to provide an improved means for mounting an engine cylinder in place. In accordance with the preferred embodiment of the present invention the engine cylinder is mounted upon two end plates which embrace the jacket. The jacket is anchored to one of the end plates and is slidably supported by the other end plate by a sliding joint which makes a sealing fit with the jacket. By this arrangement the jacket is free to expand between the supports. The ends of the cylinder within the jacket are free to expand with respect to the jacket and with respect to the supports. As a result of this arrangement any expansion of the cylinder or of the jacket can take place freely without unduly stressing the parts.

In an internal combustion engine of the type here involved it is desirable to pre-compress a volume of air which can be used for scavenging the burnt gases from the cylinder and for providing a fresh charge of air for combustion of the fuel upon the next power stroke. The back face of the cylinder moves in a chamber which constitutes a compression chamber for compressing the air. As a result it is necessary to provide a gland box for the piston at the point where the piston leaves this auxiliary gas compressor. The gland box includes gaskets for effecting a sealing fit around the piston as the piston slides within the gaskets. It is thus necessary that the center line of the gaskets be exactly coincident with the center line of the piston. The gland box is supported by a plate which is secured to the rest of the engine. In order to avoid the need for extreme accuracy in the positioning of the plate that supports the gland box there is provided a flexible bellows-like structure, one end of which is sealed to the plate and the other end of which is sealed

to and supports the gland box from the plate. As a result of this arrangement there is provided a floating support for the gland box which permits positioning of the gland box accurately with respect to the center line of the piston ring. There is thus eliminated the need for extreme accuracy in locating the bolt holes for bolting the gland box support to the rest of the structure.

Oil cooling of the pistons in an internal combustion engine has been proved to be an effective means for reducing wear on pistons, rings and cylinder walls, of preventing gumming and carbonizing of lubricating oil in the piston rod grooves, of increasing the load capacity of the engine and of reducing the tendency to develop cracked piston heads. It is one of the objects of the present invention to provide an improved means for oil cooling the pistons. To effect this result the piston rod is hollow to constitute a passageway for cooling oil to the head of the piston. A gland box which is filled with oil and maintained under pressure supplies cooling oil to the piston rod. The gland box is suitably gasketed around the piston rod to prevent creepage of any cooling oil along the piston rod into the air pressure chamber on the back side of the piston. Suitable venting means in the gasket constitute a drainage system to take care of any oil that may creep past the gasket at the inner end of the gland box. A tube in the hollow piston rod serves as a return duct to carry the oil back from the piston. The pistons are thus liquid cooled without the introduction of the usual swinging jointed pipe connections between the piston and the source of supply of the cooling liquid.

It is a still further object of the present invention to provide an improved means for adding auxiliary gas compressor units to the engine for providing additional compressed air or other gases. Such gases may be needed for operation of the engine, as for greater scavenging or the like, or for supercharging the fuel, or as may be needed for purposes apart from the operation of the engine as, for instance, for providing compressed air for auxiliary controlled devices. Since the end of the piston rod remote from the piston is guided to move in a straight line, that point may also constitute a connection point to a piston rod of an auxiliary gas compressor which may be mounted coaxially with the power piston of the engine.

The attainment of the above and further objects of the present invention will be apparent from the following specification taken in conjunction with the accompanying drawings forming a part thereof.

In the drawings:

Figure 1 is a side view, in partial section, of a two stroke cycle ignition type gas engine embodying the present invention;

Figure 2 is a sectional view taken along the line 2—2 of Figure 1 and looking in the direction of the arrows;

Figure 3 is an enlarged longitudinal sectional view of the piston and piston rod assembly and the adjacent parts of the cylinder;

Figure 4 is a sectional view taken along the line 4—4 of Figure 1 and looking in the direction of the arrows;

Figure 5 is a sectional view taken along the line 5—5 of Figure 1 and looking in the direction of the arrows;

Figure 6 is a side elevational view, in partial

section, of a somewhat modified form of engine for Diesel operation;

Figure 7 is a diagrammatic view of the engine of Figure 1 with the pistons in one extreme position and illustrating the method of ascertaining the design of a walking beam for converting the engine of Figure 1 to the Diesel type engine;

Figure 8 is a view similar to Figure 7 and showing the pistons in their opposite extreme positions;

Figure 9 is a front view of a walking beam used for converting the engine of Figure 1 from a gas engine to a Diesel engine;

Figure 10 is a front view, in partial section, of a combination engine and two stage air compressor; and

Figure 11 is an end view of the engine compressor unit of Figure 10.

Reference may now be had more particularly to the engine of Figures 1 through 5. The engine is a two cylinder four piston gas engine designed to operate on the two stroke cycle and hence to deliver two power strokes per revolution of the crank shaft. The engine comprises two substantially similar jacketed cylinders 1 and 2. Each includes an inner cylinder 3 surrounded by a jacket 4. The cylinder 3 and the jacket 4 constitute one integral casting. The cylinder 3 is provided with an opening 5 located substantially centrally of the cylinder, which opening 5 is adapted to receive the usual Diesel type injector nozzle, or a spark plug if the engine is to be used as a gas engine. The cylinder is additionally provided at one end with a group of exhaust ports 6 and at the other end with a group of inlet ports 7. The ports 6 and 7 extend around the entire periphery of the cylinder 3. The ports 6 open into a jacketed exhaust outlet 9 that leads to the atmosphere. The ports 7 open into a space 10 between the wall of the cylinder 3 and the jacket 4.

The center part of the space between the cylinder 3 and the jacket 4 is closed off by identical closures 12 and 13 to constitute a water jacket. Each closure comprises a pair of clamping rings 14 and 15 separated by V-shaped ring gaskets 16 and 17 and secured together by a series of bolts 18. By tightening the bolts 18 the gasket 16 is pressed radially outwardly into sealing engagement around the periphery of the interior of the jacket 4 and the gasket 17 is pressed radially inwardly into pressing engagement around the outer periphery of the cylinder 3. This provides a water-tight, gas-tight seal for the water chamber between the closures 12 and 13 and between the wall of the cylinder 3 and the wall of the jacket 4. At the same time if the wall of the cylinder 3 expands axially an amount greater than the expansion of the wall of the jacket 4, the cylinder 3 can slide with respect to the closures 12 and 13.

The cylinder 3 is provided with an additional series of ports 20 and 21 at opposite ends thereof, both of which series of ports extend around the periphery of the cylinder and open into the space 10 between the cylinder 3 and the jacket 4. The space between the cylinder 3 and the jacket 4 is thus divided into a central water compartment which is incommunicable with the two end air compartments 10. The two end compartments communicate with one another through a duct 23 that also communicates through a check valve 24 to the atmosphere in the case of a Diesel engine, and in the case of a gas engine to a fuel-air line that leads from the usual carbureting device.

This permits the flow of an air-gas mixture from the usual carbureting device into the duct 23 when the pressure in the duct 23 is below that on the outlet side of the valve 24, but which prevents the flow from the duct 23 through the check valve when the pressure in the duct 23 is above that in the fuel-air line.

The two cylinders 1 and 2 are supported by a pair of end plates 30 and 31. To that effect the jacket 4 of each cylinder has a peripherally extending flange 32 adjacent to but spaced from one end of the jacket and integral therewith. This flange is bolted to the end plate 31 by a series of bolts 33 and 34, as may be seen in Figures 1, 4 and 5. The bolts 33 extend from the left hand side of the flange 32 through the end plate 31 in which they thread. The bolts 34 extend from the right hand side of the plate 31 through the plate 31 and through the flange 32 and receive a nut on the left hand side of the shank of the bolt. The head of each bolt 34 rests in a pocket or recess 35 in the plate 31, which pocket is of sufficient size to permit gripping of the head of the bolt by a suitable tool for turning of the bolt. The reason for the different arrangement of the bolts 33 and 34 will be apparent as this description proceeds. It is sufficient here to state that by the arrangement thus far described the jacket 4 of the cylinder 2 is rigidly secured to the end plate 31.

The end plate 30 slidably supports one end of the jacket 4 of each cylinder 1 or 2. To this effect the end of the jacket extends into a circular hole through the plate 30. A ring 36 is located on the outside of the jacket and is slidable thereon. A gasket 37 is positioned around the outside of the jacket between the ring 36 and the end plate 30. The ring 36 corresponds to the flange 32 differing therefrom only in that the ring is not integral with the jacket, whereas the flange is. The ring 36 is secured to the end plate 30 in much the same manner as the flange 32 is secured to the plate 31, as by bolts 33' which correspond to the bolts 33, and bolts 34' which correspond to the bolts 34. The bolts 33' screw into the plate 30 whereas each bolt 34' has its head seated in a pocket in the plate 30 and its shank extending through the plate and through the ring 36 to receive a tightening nut 39 (Fig. 3). The gasket 37 is tightly pressed by the bolts to effect a liquid-tight, air-tight seal around the outer periphery of the jacket and between the jacket and the plate 30. A similar but much thinner gasket is provided between the flange 32 and the plate 31, this last mentioned gasket being much thinner because there is no sliding movement between the plate 31 and the flange 32. By the arrangement thus described it is apparent that the right hand end of each cylinder jacket is rigidly secured to the end plate 31, whereas the left hand end of each cylinder jacket is slidably supported by the end plate 30. The ends of the cylinders 3 extend through the end plates 30 and 31 but are freely slidable with respect thereto. Thus both ends of each cylinder are free to expand lengthwise, and one end of the jacket is anchored, whereas the other end is free to expand lengthwise.

A crank case 42, which is rectangular in cross section, is bolted to the end plates between the two cylinders 1 and 2, as may be seen from Figures 1, 2 and 6. There is a small space 43 between the crank case and each cylinder, which space is of greater width adjacent the ends of the

cylinders than at the center thereof. Each end plate is provided with a rectangular crank case opening which is in line with similar openings 44 in the end plates 30—31. The crank case 5 has an inwardly extending flange 45 around each end opening therein, which flange is bolted to the end plates 30 and 31 by bolts 46 that extend through the flange and thread into the end plates 30 or 31, as may be seen from Figures 1 and 5.

A crank shaft 48 is journalled in suitable anti-friction bearings 49 carried by the crank case 42. The crank shaft 48 includes two crank throws 50 and 51, 180° apart. The axis of rotation of the shaft 48 is located centrally between the ends 15 of each cylinder, midway between the two cylinders, with its axis at right angles to the plane determined by the longitudinal axes of the cylinders 3. The crank throw 50 has two crank connecting rods 52—53 secured thereto, and the crank throw 51 has two crank connecting rods 54 and 55 connected thereto. The crank connecting rods 52 and 54 extend from the left hand side of the crank case as seen in Figure 2 and the rods 53 and 55 extend from the right hand side of the crank case.

Each cylinder 3 is provided with opposed double acting pistons 60 and 61 of identical construction. The piston 60 and its associated piston rod and gland box construction is illustrated 30 more fully in Figure 3. The piston 60 is provided with a chamber 62 at the head thereof, which chamber is closed at the front by the front working face 63 of the piston, and is closed at the back by a rear wall 64 which is provided with a central opening into which a hollow piston rod 65 extends, the piston rod being provided with a parallel flange 66 for bolting to the wall 64 of the piston. The piston rod 65 is secured at its opposite end to a fitting 68 which is mounted for oscillation in a straight line, as will be herein-after described. A pipe 69 extends through the interior of the hollow piston rod 65 and extends into the piston and is supported at its end by the piston. The space between the pipe 69 and the 35 inside of the bore of the piston rod 65 constitutes a passageway for the forcing of cooling oil into the chamber 62 for cooling the piston. The oil returns from the chamber 62 by way of a passageway 70 to the pipe 69, and through the pipe 69 to an outlet 71 in the fitting 68, from which it flows into an end chamber which will be more fully described as this description proceeds.

The piston rod 65 is supported by a gland box 74. The gland box includes an end plate 75 having a metallic bellows 76 sealed thereto at 55 77. The inner rim of the bellows is sealed at 78 to a metal tube 79 that has an end closure 80 through which the piston rod 65 slides. A sealing gasket 81 surrounds the inner end of the piston rod 65 and bears against the end closure 80 and is pressed thereagainst by a sleeve 82 that has an inturned end 83. A sealing gasket 84 presses against the piston rod 65 at the end of the sleeve remote from the piston. Another 60 end plate 86 surrounds the piston rod 65 and presses against the gasket 84. A pair of through bolts 87, which are 180° apart, extend from the end plate 86 to the end plate 80 (Figs. 1 and 5) and serve to draw them tightly together, thus compressing the gaskets 81—84 between the sleeve 82 and the end plates 80 and 86 respectively. The sleeve 82 is thus supported from the end plate 75 through the flexible bellows 76 so that if the plate 75 is a slight amount off center 65 with respect to the longitudinal axis of the cyl-

nder 3 the sleeve 82 is free to adjust its position so that its center coincides with the longitudinal axis of the cylinder 3.

A pipe 90 maintains a continuous flow of oil under pressure to the interior of the sleeve 82. This oil flows from the sleeve to the interior of the piston rod 65 by way of a series of openings 91 (Fig. 3) in the piston rod, and then flows into the piston, thence through the passageway 70 and pipe 69 to the outlet 71, thus maintaining a continuous flow of cooling oil to the head of the piston.

It is desirable that there shall be no creepage of oil from the sleeve 82, on the outside of the piston rod 65, past the sealing gaskets 81. To prevent such creepage of oil the gasket 81 is provided with a plurality of by-passes 93 that extend from the piston rod 65 to the outside of the sleeve 82. Thus any oil under pressure within the sleeve 82 which may happen to creep past part of the gasket 81 will encounter the by-pass 93 and flow outwardly therethrough without creeping along the rest of the piston rod past the end plate 80. The oil which flows out through the by-pass 93 ultimately comes back to the same place into which the oil from the outlet 71 flows. The piston, piston rod and gland box assembly 14 constitute a sub-assembly for attachment to the cylinder in a manner to be hereinafter set forth.

Housings 100 and 101 of identical construction are secured to the end plates 30 and 31 respectively. Each housing has two similar straight line motion mechanisms 102 and 103 mounted therein. The straight line motion mechanism 102 is of a construction such as is shown more particularly in my Patent No. 2,198,635, issued April 30, 1940, to which reference may be had for a more complete description thereof. Briefly, the straight line motion mechanism includes two similar links 104-105 pivoted about fixed pivots 106-107 and supporting a pair of movable pivots 108-109. A rigid walking beam 110 is pivoted to the two movable pivots 108 and 109. The fitting 68 is secured to the walking beam 110 by a pivot pin 111 the center of which is on the perpendicular bisector of a line joining the centers of the pivots 108 and 109, as may be seen from Figure 1. The distance between the centers of the fixed pivots 106-107, the lengths of the links 104-105, the distance between the movable pivots 108 and 109 and the distance of the pivot 111 from the movable pivots are so proportioned that the locus of the point 111 is a straight line within the limits of travel of the piston rod. The proportions of the links required for producing a straight line motion of the point 111 may be obtained from my patent above referred to. The lower end of the walking beam 110 is pivotally connected to the crank connecting rod 55 by a pivot pin 112, as may be seen from Figures 1 and 4. The straight line motion mechanism 102 thus connects the piston rod of the upper right hand piston of Figure 1 with one connecting rod in such a manner that the end of the piston rod is guided by the straight line motion mechanism in a straight line and transmits its power through the walking beam 110 to the connecting rod 55, thence to the crank shaft. In a like manner the straight line motion mechanism 103 connects the lower right hand piston rod with the crank connecting rod 53 by a pivot pin 113.

The housing 101 has a rectangular opening 115 covered by a closure plate 116 bolted thereto.

By removing the plate 116 access is had to the interior of the housing 101. The end of the housing 101 also has a wall 120 in which an opening 117 is formed and in which there are also formed openings for each of the cylinders 3, as indicated at 121 in Figure 3. The end plates 75 of the gland box 74 are bolted to the plate 120 of the housing 101 as by bolts 126. The wall 120 extends beyond the main body of the housing to form an outwardly extending peripheral flange 123 which is bolted to the end plate 31 by bolts 124, as may be seen from Figure 4. Thus the housing 101 is secured to the end plate 31.

An explanation will now be given of the manner of assembling the engine. The closures 12 and 13 for forming the water chambers of the cylinder are individually assembled. Thereafter the two cylinders are mounted on the end plates 30 and 31 in the manner previously described and then the crank case 42 is mounted between the end plates. At that time access to the bolts 46 is obtained by way of the opening 44 in the end plates 30 and 31 and the corresponding opening in the crank case. This constitutes one assembled unit.

The straight line operating mechanisms 102 and 103 are then assembled within the housing 101 which, at that time, is preferably not yet bolted to the end plate. The piston and piston rod and the associated gland box 74 are then assembled together. The plate 75 of the gland box is then bolted to the plate 120 of the housing 101. At that time access to the bolts 126 is had through the opening 117 of the housing 101. The fitting 68 at the end of the piston rod assembly 65 is then secured to the corresponding straight line motion mechanism by inserting the pivot pin 111 through the walking beam 110 and the fitting 68. The housing 101 is then brought up towards the end plate 31 and the two pistons carried by the housing 101 are then fitted into the corresponding cylinders 3 into which they slide. At the time the housing 101 with the pistons extending therefrom is brought up against the plate 31 and before the pistons have been slid into the cylinders the pistons may be very slightly out of alignment with the cylinders. If this is the case they need merely be pushed up or down or sideways, as the case may be, to bring them into the cylinders, the flexible metal bellows 76 permitting such movement of the gland box 74. Thereafter the pipe 90 can be threaded into the gland box from outside the housing 101. It is then a simple matter to connect the respective crankcase connecting rods 52, 53, 54 and 55 to the respective walking beams of the straight line motion mechanisms. The provision of the removable plate 116 permits reaching into the housing 101 for making those connections. Thereafter the closure plate 116 may be bolted in position to close the housing 101.

It is to be noted that the flange 123 of the housing 101 bears against one side of the end plate 31, a suitable sealing gasket being interposed. It is for that reason that the bolts 39 that secure the cylinders 1 and 2 to the plate 31 are mounted with their heads on the opposite side of the plate 31. In view of the fact that the crank case is close to the cylinder there may be difficulty in inserting a wrench in the space between the cylinder and the crank case for tightening the adjacent bolts that secure the cylinder to the end plate 31. It is for that reason that the bolts 34 that are located adjacent the crank case are

mounted with their heads on the right hand side of the plate 31, rather than on the left hand side of that plate. Since the flange 123 and the wall 120 of the housing 101 must bear against the end plate 31, that plate is provided with the recesses 35 for the heads of the bolts 34 so that the heads of those bolts do not prevent the wall 120 and its gasket from lying flat against the plate 31.

Each of the two end housings 100—101 for the straight line mechanisms is designed as a single piece. The two pistons that are associated with each end housing can be removed by disconnecting their associated connecting rods, then unbolting and removing the housing. When the housing is removed all of the parts of the straight line mechanism within it are accessible.

The four pistons of the two cylinders are so connected to the two crank throws that the movement of the pistons in one cylinder are displaced 180° from the movement of the corresponding pistons in the other cylinder. To permit two pistons in the same cylinder to be connected to adjacent throws on the same crank shaft the walking beams 110 and 110' at the opposite ends of each cylinder are inclined laterally in opposite directions, as may be seen from Figure 4, but the axes of all bearings and pins that are associated with them are made parallel to the axis of the crank shaft.

An explanation will now be given of the mode of operation of the engine. Assume that the pistons 60 and 61 are in the position illustrated in Figure 1. The cylinder 3 has been scavenged of the burnt gases from the previous working stroke and is now filled with an air-gas mixture which entered the cylinder by way of the ports 7. As the pistons approach one another they first close the intake ports 7 and then close the exhaust ports 6. Upon further movement of the pistons towards one another the air-gas mixture within the cylinder is compressed. As the pistons approach one another after the ports 7 are closed by the piston 61 the chamber at the back of the piston is being increased in size. Since that chamber communicates with the chambers 10 by way of the ports 20—21 there is a resulting reduction of pressure in the chambers 10—10, with the result that an air-gas mixture is drawn in from the carbureting device by way of the check valve 24. Thus as the pistons continue to move towards one another within the cylinder they continue to draw in the air-gas mixture from the carbureting device into the chambers 10. When the pistons have approached one another the full extent of their travel ignition of the fuel takes place, thus forcing the pistons apart. This is the power stroke of the cylinder. As the pistons 60 and 61 recede from their innermost position towards the position illustrated in Figure 1 they compress the air-gas mixture on the back sides of the pistons. This results in the immediate closing of the check valve 24, with the result that the continued recession of the pistons from one another continues the compression of the air in the compression chamber rearward of the pistons and including the chambers 10 and duct 23. As the pistons continue to recede under the pressure of the burnt gases in the cylinder 3, the piston 60 ultimately commences to uncover the ports 6, before the piston 61 has commenced to uncover the ports 7. As a result of the uncovering of the ports 6 the burnt gases within the cylinder are discharged through the ports 6 and to the exhaust outlet 9. A moment after the first uncovering of the ports 6 the piston 61 uncovers the ports 7. This causes the compressed air-gas mixture from

the chamber 10 to move through the ports 7 into the cylinder and force the remaining burnt gases out of the cylinder through the ports 6 and fill the cylinder with a fresh air-gas mixture for the next cycle of operation.

During the power stroke of the pistons the piston rod moves the walking beam 110 about its pivots, to the position illustrated in full lines in Figure 1, and it moves the corresponding walking beam 110' to the position illustrated in dotted lines in Figure 1 and thus through the connecting rods 55 and 52 actuate the crank shaft.

The pistons are maintained cool by circulating oil under pressure through the pistons. The pipes 90 are connected to an oil pump which supplies oil under pressure to the pipes. The oil flows through a pipe 90 into the gland box 74, thence through the openings 91 (Fig. 3) into the piston, then out again by way of the passageway 70 in the piston and pipe 69 to the outlet 71, from which it flows into the end casing 100 or 101, where it is again picked up by the oil pump and recirculated. As there is no possibility of the cooling oil flowing into the cylinder in view of the drainage by-pass 93, the oil that is circulated in the pistons is not contaminated and hence does not have to be replaced by fresh oil at frequent intervals.

It is to be noted that the pistons of the two cylinders are 180° apart so that while the pistons of one cylinder are making the power stroke the two pistons of the other cylinder are making the compression stroke. The impulse that is set up by an explosion within a cylinder acts equally and in opposite directions on both pistons and on the two cranks 180° apart, and reacts equally in opposite directions through the length of the crank case. Hence each dynamic force is balanced by a corresponding dynamic force of equal value acting in the opposite direction. With the cranks thus spaced 180° apart these forces form a balanced couple that has a minimum tendency to distort the crank shaft and little tendency to built up high pressures on the main bearings.

As to the balance of the inertia forces, all moving parts that are associated with each cylinder are in two duplicate groups and the parts of one group are substantially duplicates of the corresponding parts of the other group. With crank throws 180° apart, corresponding reciprocating parts move simultaneously at the same speed but in opposite directions. Hence the inertia effect of each part in one group is balanced by the inertia effect of a corresponding part in the other group.

Because of these two balanced effects an engine of the present design does not require a heavy foundation.

The bearings of the straight line mechanism can be either plain bearings or anti-friction bearings. In the event that play develops in the bearing of the straight line mechanism there can be no pounding as a result because whereas in the four cycle engine the forces which act on the bearings reverse, in the two cycle engine they act continuously in one direction. This characteristic permits both of the two connecting rods that are brought from opposite directions to the same crank throw to have full width bearing surfaces against the crank. This is accomplished by so designing the bearing surface on the end of each connecting rod that it will encircle slightly less than 180° of the crank bearing surface, and then holding both ends in place

either by a pair of floating clamp rings that encircle the outside half bearing shells of both rods or by two half rings each of which is bolted to the end of one rod and encircles the half bearing shell of the other.

Reference may now be had more particularly to the embodiment of the invention illustrated in Figure 6. Insofar as the structure of this engine is the same as that of the engine previously described, similar reference numerals have been used. The engine of Figure 6 differs from that of Figure 1 mainly in that the end housing 101 is provided with two additional cylinders 135-136 of identical construction, to form additional air compressors. Each of the cylinders 135-136 is provided with a piston 137 and a connecting rod 138 that is connected to the fitting 68 that joins the straight line motion mechanism with the power piston rod. The cylinder 135 connects with the duct 23 by way of a duct 139. When the piston rod moves to the left, as seen in Figure 6, the piston 137 is also drawn to the left to draw air from the atmosphere into the cylinder 135 by way of the duct 139 and the check valve 24. When the piston 137 reaches its extreme left hand position and then reverses its direction of travel, the check valve 24 closes, and the piston 137 compresses the air within the chamber 135 and adds it to the air being compressed at the back of the pistons 60 and 61 of Figure 1. This provides an additional amount of compressed air for scavenging the cylinder and for furnishing compressed air to the cylinder.

When the auxiliary cylinders 135 and 136 are used for increasing the scavenging ratio, as illustrated in Figure 6, they require no additional valves and are light in weight, hence do not increase the cost of the engine by any appreciable amount. Insofar as the cylinders 135-136 increase the scavenging ratio they permit an increase in the output of the engine.

Figure 6 illustrates one way of connecting a compressor to a piston rod of the engine of Figure 1. In the embodiment illustrated in Figure 6 the compressor formed by the cylinder 135 supplies its compressed air to the engine. It may, however, be used to supply its compressed air to any other device or devices that may utilize compressed air, since the device 135 is a compressor operated by the engine.

While I have shown the engine as mounted with the cylinders horizontal, it is apparent that end plates 30-31 can be supported in a horizontal position so that the cylinders are vertical, without affecting the mode of operation of the engine. It is further apparent that while the engine has been illustrated as operating on the Diesel principle, it may operate as an ignition type engine by providing means for admitting gas fuel immediately preceding or during the early stage of the compression stroke, and the usual spark plugs adjacent the inlet ports 5, as is well known in the gas engine art.

It is sometimes necessary to provide a Diesel type engine which may thereafter be converted to a gas engine. This is particularly so in oil drilling operations. A Diesel type engine is used for operating the drilling mechanism. Later the same engine is to be used to operate the oil pump. At that time gas is available and it is therefore desirable to operate the engine on the gas principle. The engine of Figures 1 to 5 may be converted from the gas engine to a Diesel engine or vice versa with a minimum change in parts.

Only the walking beam 110 between each piston rod and its associated connecting rod need be changed. Assume that an engine such as shown in Figure 1 has been constructed to operate as an ignition type gas engine and it is desired to convert that engine to a Diesel engine. In a Diesel engine the clearance volume between the opposite pistons during the compression stroke is less than in an ignition type gas engine. It is thus necessary to increase the inward stroke of the pistons in order to decrease the clearance volume to that required for Diesel operation (a compression ratio of 16 to 1). In accordance with the principles of the present invention all

of the increase in piston travel can be made to take place on the inward end of the stroke so that at the outward end of the stroke the position of the piston with reference to the port openings 6-7 in the cylinder wall will be unchanged. Thus the change over from gas to Diesel operation or vice versa can be made without changing the piston or the connecting rod. As previously stated, the only change that need be made is to replace the walking beam 110 by another walking beam.

An explanation will now be given of the manner of locating the pivots of the new walking beam, for which purpose reference may be had to Figures 7 and 8. In Figure 7 the pistons 60-61 are shown in the outermost position being connected to a walking beam supported by the links 104 and 105 at the pivot points 108 and 109, the walking beam being pivoted to the piston rod at 111. The point 140 represents the point of connection between the connecting rod 55 and the walking beam for gas engine operation. With the connecting rod 55 as a radius and the center of the crank 48 as a center an arc 141 is drawn on the walking beam. The piston 61 is then moved inwardly to its innermost position for gas operation, which is the position illustrated in full lines in Figure 8. The pivot pin which joins the connecting rod 55 with the walking beam at 140 is then removed. This permits shifting of the piston 61 to a position illustrated in dotted lines at 61' which is the innermost position required for Diesel operation. At that time the pivots 108, 109 and 111 move from the positions illustrated in full lines in Figure 8 to the position illustrated in dotted lines. The curve 141 is now in the position illustrated in Figure 8. The end of the connecting rod 55 is then swung about its new center 48 of the crank thereby drawing an arc 142. The point of intersection of the arcs 141 and 142 represents the required new pivotal connection between the connecting rod 55 and the walking beam. If the connecting rod is pivoted to the walking beam at this intersecting point, indicated at 143, the pistons 61 will be in their dotted line position of Figure 8 when the crank 48 is in one extreme position and will be in the full line position of Figure 7 when the crank is in its opposite extreme position. Thus by shifting the point of pivotal connection of the connecting rod 55 with the walking beam from the point 140 to the point 143 the stroke of the piston 60-61 is increased. All of the increase in stroke takes place during the inward movement of the piston, so that the outermost position of the piston 61 remains the same. The walking beam may be provided with two points for pivotal action with the connecting rod. If it is found that the two required points of pivotal connection are so close together as not to allow room for two separate pins, two

different walking beams may be provided, one for use when the engine is operating as an ignition type gas engine and the other when it is operating as a Diesel engine.

Figure 9 shows on an enlarged scale the walking beam used for Diesel operation. The pivot points 108, 109 and 111 are the same relative spacings as in the walking beam illustrated in Figures 7 and 8. The pivot point 143 is located at the intersection of the curves 141 and 142 which is displaced slightly from the center line 145, said center line being the perpendicular bisector of the line 146 joining the centers of the pivots 108—109.

When the engine operates as a Diesel type engine the check valves 24 open directly to the atmosphere. The opening 5 (Fig. 1) of the engine is provided with a Diesel type fuel injector in lieu of a spark plug such as is used when the engine operates as a gas engine. In operating as a Diesel engine when the pistons are in the position illustrated in Figure 1 the cylinder 3 has been scavenged of burned gases from the preceding stroke and is now filled with air at atmospheric pressure. As the pistons approach one another they first close the air intake ports 7 and then close the exhaust ports 6 and then, upon continued inward movement of the pistons, they compress the air within the cylinder. When the pistons reach their innermost limit of motion a charge of fuel oil is injected into the cylinder by way of the opening 5, as is usual in Diesel type engines. During this inward movement of the piston 6 air has been drawn through the check valve 24 into the space in back of the pistons, in the manner previously described. When the fuel is injected into the space between the pistons combustion takes place thus forcing the pistons apart to make the power stroke of the engine. During their rearward movement the pistons compress the air in back of the pistons, the pistons first uncover the exhaust ports 6 and then the air inlet port 7 so that the compressed air in the chamber 10 first sweeps the burned gases from the cylinder 3 and then fills the cylinder with fresh air for the next stroke of the piston.

The engine above described, whether operated as a Diesel engine or as an ignition type gas engine, may be used for furnishing the power for operating a compressor. Figures 10 and 11 illustrate such an engine used to operate four compressor cylinders constituting a two stage compressor. In Figure 10 the engine is of the kind illustrated in Figure 1. The housing 101 has two similar air compressor cylinders 150 and 151 secured thereto in any desired manner, as by bolting or the like. The cylinders preferably, although not necessarily, constitute one integral casting and are provided with a cooling water jacket 152. Identical pistons 153 and 154 are located in the cylinders 150 and 151 respectively. The pistons are provided with piston rods 155 and 156 respectively. The piston rods 155 and 156 are pivotally connected to connecting rods 53' and 55' respectively, which correspond respectively to the connecting rods 53 and 55 of the engine of Figure 1. The connecting rods 53' and 55' are provided with offsets for furnishing the points of pivotal connection 157 and 158 respectively, with the respective piston rods. The piston rods cannot conveniently be connected to the pivot pins 112 and 113 respectively, because those pivots are too close together and there-

fore there is not enough space for the two cylinders 150—151.

The housing 100 is provided with a set of cylinders 163 and 164 similar to the cylinders 150 and 151 and similarly connected to the corresponding connecting rods on the opposite sides of the engine, which connecting rods are of the same shape as the connecting rods 53' and 55'. Each of the four cylinders are air compression cylinders and are provided with the usual inlet and outlet air ports 166 and 166' controlled by check or other type of valves, as is well known in the compressor art. In the preferred construction three of the cylinders receive air from the atmosphere and deliver it to a single manifold or tank at a gauge pressure of 30 pounds per square inch or 45 pounds absolute pressure. The fourth cylinder receives air from that compression tank at the intake side of the cylinder and delivers air to another tank at a pressure of 135 pounds per square inch absolute. The four compressor cylinders 150, 151, 163 and 164 thus comprise a two stage compressor designed to deliver air at approximately 120 pounds per square inch gauge pressure. The valves and unloading devices used in connection with the compressor may be of the well known types now in common use.

The crank shaft 48 of the engine of Figures 1 and 10 also drives a suitable heavy fly wheel 170 for the usual purposes.

In the design shown the engine piston and the compressor piston have equal strokes. This is not an indispensable part of the present invention since any desired ratio of the stroke of the engine piston with respect to the compressor piston can be obtained either by varying the ratio of the engine piston stroke to the throw of the crank shaft 48 or by connecting the air compressor piston rods 155—156 to the walking beam of the corresponding straight line mechanism 102—103.

In the engine compressor unit of Figure 10 the scavenging air cylinders 135—136 of Figure 6 have been omitted for the sake of simplification. It is, however, to be understood that those cylinders may be provided in addition to the compressor cylinders illustrated in Figure 10. The scavenging cylinders 135—136 act at such low pressures and do so little work that they do not cause any appreciable unbalance of the engine or wear on the pivot pins that connect those pistons with the walking beam structure. The scavenging air cylinders are provided only when operating the engine as a Diesel engine, not while operating as a gas engine.

By making the pistons of the compressor single acting they can be splash lubricated by the splash lubricating system of the engine. Because the air compressor pistons are single acting and their piston rods are connected to the linkage in the manner indicated, the thrusts that are set up while compressing the air act upon the pivot pins in the same directions as those that are set up by power pistons of the engine with advantages that have been discussed above in connection with the discussion of the balance in the operation of the engine.

The only important friction generating surfaces that result from the addition of the air compressor cylinders to the engine are the rubbing surfaces of the air compressor pistons on their cylinder walls. Because the angularities of the connecting rods that drive the air compressor pistons are small these added frictional losses will also be quite small and the overall me-

chanical efficiency of the combination engine and air compressor will be higher than that of two independent units coupled together.

The engine of Figure 10 is particularly adapted for furnishing compressed air in a pneumatic power system, such as shown in my pending application entitled, "Pneumatic power unit," filed of even date herewith. If the unit of Figure 10 is designed to furnish compressed air to such a system the low pressure air ports 166 are all connected to a common low pressure main and the outlet or high pressure ports 166' are all connected to a high pressure main, it being understood that each cylinder inlet and outlet is provided with an automatic valve. In the case of the inlet valves the valves are spring seated and arranged to open whenever the pressure in the cylinder falls below the pressure of the main to which the inlet ports are connected. In the case of the outlet valves the valves are also spring seated and are arranged to open whenever the pressure in the cylinder exceeds the pressure in the main to which the port is connected and to close whenever the pressure in the cylinder is less than the pressure in the main to which the valve is connected. Such valves are well known and may be of the type described and illustrated in Marks' Mechanical Engineers Handbook, third edition, page 1866. If it is desired to provide for automatically disabling any selected one or more of the compressor cylinders to reduce the compressed air output of the unit, the inlet valves may be provided with pneumatically controlled unloading devices of the type known in the art. One suitable type of unloading device is illustrated in Figure 43 of my co-pending application for Letters Patent covering "Pneumatic power unit," filed of even date herewith. This is the type of unloading device described and illustrated in Marks' Mechanical Engineers Handbook, third edition, page 1873.

While the four air compressor cylinders of the engine of Figure 10 have all been shown as being of the same diameters, this is not indispensable as they may be of different diameters in order that different outputs may be obtained by using different combinations of compressor cylinders.

In compliance with the requirements of the patent statutes I have here shown and described a preferred embodiment of my invention. It is, however, to be understood that the invention is not limited to the precise constructions here shown, the same being merely illustrative of the principles of the invention. What I consider new and desire to secure by Letters Patent is:

1. An engine having two parallel cylinders, opposed pistons in each cylinder, a crank shaft between the two cylinders and rotatable about an axis at right angles to the longitudinal axes of the cylinders, said crank shaft having two crank throws substantially 180° apart, driving connections between one crank throw and diagonally opposite pistons of the two cylinders, driving connections between the other crank throw and the remaining two diagonally opposite pistons, a crank case for the crank shaft, said case being between the cylinders and open at both ends, and housings at the opposite ends of the crank shaft, each housing overlying an end of both cylinders and an open end of the crank case and supporting at least parts of said driving connections.

2. In an engine having a piston, a piston rod connected at one end to the piston, a straight line motion mechanism including a beam pivoted intermediate its ends about a pair of axes so spaced

that a point on the beam moves in substantially a straight line, a pivotal connection between the piston rod and a straight line motion point of the beam, a crank shaft rotatable about an axis spaced from and at right angles to the longitudinal axis of the piston, and a driving connection including a connecting rod between the crank shaft and the beam.

3. A device of the character described comprising a linkage including a pivoted beam having a point thereon adapted to oscillate over a limited distance along a substantially straight line, a piston movable in a direction parallel to said line, a piston rod connecting the piston with the beam at said point on the linkage, a second piston opposite the first piston and movable towards and away therefrom, a piston rod connected to the second piston, a second linkage similar to the first linkage and similarly connected to the second piston rod, a crank shaft located centrally between the pistons and at right angles to their line of motion, and separate crank connecting rods connected to the respective beams at points movable in directions substantially opposite to the directions of movement of the respective straight line motion points.

4. In combination with a pair of coaxial oppositely reciprocating pistons, piston rods for the respective pistons, a crank shaft between and at right angles to the pistons, straight line motion mechanisms pivoted about fixed axes adjacent each piston rod and each including a beam one point of which is constrained by the mechanism for movement in a straight line, a pivotal connection between said point and the adjacent piston rod, and connecting rods between the crank shaft and the respective beams.

5. In an engine having a pair of opposed pistons and piston rods, two walking beams one for each piston rod, pivotally mounted means for guiding the movement of each beam so that a point thereof moves in substantially a straight line, a pivotal connection between each piston rod and the straight line motion point of its associated beam, a crank shaft substantially equidistant from the two pistons and with its axis of rotation at right angles to the directions of travel of the pistons, and connecting rods extending in opposite directions from the crank shaft to said walking beams.

6. An engine comprising a cylinder open at both ends, opposed double acting pistons in said cylinder, closures for the opposite ends of the cylinder, piston rods extending from the pistons through the respective end closures, a crank shaft located substantially centrally of the cylinder and with its axis of rotation at right angles to the longitudinal axis of the cylinder, an open ended crank case for the crank shaft, separate housings over each open end of the crank case, said housings extending over the adjacent ends of the cylinder, straight line motion mechanisms within the respective housings, a connection between each piston rod and a straight line motion point of the associated mechanism so that the mechanisms guide the piston rods in straight lines, and connecting rods extending from the crank shaft into the respective housings and connected to the respective straight line motion mechanisms.

7. In an engine having a cylinder, a double acting piston therein, a piston rod connected at one end to the piston, a straight line motion mechanism including a beam a point on which moves in substantially a straight line, a pivotal connection between the piston rod and a straight line

motion point of the beam, a crank case extending lengthwise of the cylinder for substantially the full length thereof, a crank shaft rotatable in said crank case about an axis spaced from and at right angles to the longitudinal axis of the piston, and a driving connection including a connecting rod between the crank shaft and the beam.

8. An engine comprising a cylinder open at both ends, a pair of opposed double acting pistons in said cylinder, piston rods for the pistons, a casing at each end of the cylinder, a crank case between the casing and closed by said casings, a crank in said crank case and extending at right angles to the longitudinal axis of the cylinder, straight line motion mechanism in each casing, each mechanism having a straight line motion point the locus of which is parallel to the longitudinal axis of the cylinder, a driving connection between said points and the respective piston rods, and connecting rods connecting the crank shaft and the straight line motion mechanisms.

9. An engine comprising an open ended cylinder and an open ended crank case with the open ends of both facing in the same direction, a housing over the open ends of the cylinder and the crank case, a piston in the cylinder, a piston rod connected thereto and extending into the housing, a crank shaft in the crank case, a connecting rod extending therefrom into the housing, a straight line motion mechanism mounted in the housing and connecting the connecting rod with the piston rod, the mechanism having a straight line motion point the locus of which is parallel to the longitudinal axis of the cylinder, and the piston rod being connected to said mechanism at said straight line motion point thereof.

10. In an engine having a piston, a piston rod connected at one end to the piston, a straight line motion mechanism including a beam pivoted intermediate its ends about a pair of axes so spaced that a point on the beam moves in substantially a straight line, a pivotal connection between the piston rod and a straight line motion point of the beam, a crank shaft rotatable about an axis spaced from and at right angles to the longitudinal axis of the piston, a driving connection including a connecting rod between the crank shaft and the beam, a cylinder and a piston therein in alignment with the first mentioned piston, and a driving connection between the second mentioned piston and a straight line motion mechanism.
11. In combination with a pair of coaxial oppositely reciprocating pistons, piston rods for the respective pistons, a crank shaft between and at right angles to the pistons, straight line motion mechanisms pivoted about fixed axes adjacent each piston rod and each including a beam one point of which is constrained by the mechanism for movement in a straight line, a pivotal connection between said point and the adjacent piston rod, connecting rods between the crank shaft and the respective beams, separate cylinders spaced from the pair of oppositely reciprocating pistons, pistons reciprocable in said last mentioned cylinders and driving connections for said last mentioned pistons extending from the respective ones of the last mentioned pistons to the respective straight line motion mechanisms.

ALLEN M. ROSSMAN.
